HAIRPIN

Frank E. De Long, Washingtonville, Pa.

Application February 3, 1932. Serial No. 590,594

5 Claims. (Cl. 132—50)

This invention relates to hair-pins, and it has for its chief aim the provision of a hair-pin capable, by torsional clamping action, of effectively resisting dislodgement after placement in the hair.

A further object of my invention is to secure the indicated desideratum in a hair-pin which lends itself to very economic production in quantity from wire or other strip or strand material of a springy nature.

Still other objects and attendant advantages of this invention will be manifest from the following detailed description considered in connection with the attached drawing; wherein Fig. I is an illustration, drawn to an enlarged scale, showing my novel hair-pin in side elevation.

Fig. II shows the hair-pin in bottom plan.

Fig. III is an illustration corresponding to Fig. I showing a modified form of my invention; and, Figs. IV and V are respectively side edge and bottom plan views of the hair-pin of Fig. III.

Referring first to Figs. I and II of the drawing, the hair-pin there illustrated is made from a single length of spring wire, by medially bending the wire, with resultant formation of a rounded head at 3 and a pair of prongs 4. From Fig. I it will be observed that the prongs 4 extend downward in spaced parallel relation from the head 3 to outward directed bights forming an eye 5, and that the lower end of this eye 5 is defined by overlap crossing of the ends 6 of the prongs at a point 7 substantially midway of the length of the pin.

Incident to thrusting the pin into the hair, the hair strands caught between the prong ends 6 act to wedge the crotch 8 at the crossing of the prongs 4, thereby forcing the legs apart perpendicular to their common plane, and causing the pin to twist on its longitudinal axis. Upon passage of the eye 5, some of the hair strands are gripped in the narrowed space 9 between the parallel portions of the prongs 4 at the region of the head 3 of the pin. Due to the inherent springiness of the wire from which the pin is made, and by virtue of the axial twist induced incident to its placement, the pin is maintained under constant torsional strain when in use. Accordingly the hair is clamped by prongs 4 and caused to wrap itself about the pin, so that the latter is effectively anchored against easy dislodgement, and also hidden so as to be almost or practically invisible. The gripping action of the pin is to a great extent enhanced by bunching and trapping or locking of some of the hair

strands within the loop of the pin, which includes the eye 5 as well as the space 9, above the point 7 of crossing overlap of the prongs 4.

In the modified form of hair-pin illustrated in Figs. III—V, the prongs 4a are substantially parallel, and, at a point intermediate the length of the pin, formed with inwardly-directed opposing indentations or bights 10 whereof the median portions overlap as shown in Fig. III. These bights 10, it will be noted from Fig. V, are moreover oppositely disposed at an angle in respect to the plane of the hair-pin. As a consequence of this construction, there is formed, immediately beneath the head 3a, a vertically elongate eye 5a in the plane of the pin, as shown in Fig. III, and, immediately below said eye, a smaller substantially circular eye 11 at right angles to the plane of the pin as shown in Fig. IV. When thrust into the hair, the modified hair-pin, like the one first described, twists on its longitudinal axis, thereby wrapping the hair about itself and maintaining itself in position against displacement by maintenance of torsional strain under the springiness of the wire, and also hides itself in the hair. The capacity of the modified hair-pin to resist withdrawal is greatly increased through packing of different bunches of hair strands in twisted angular relation within the two eyes 5a and 11, which, as already explained, lie perpendicular to each other. Here, again, as in Figs. I and II, the legs of the pin are forced apart perpendicular to their common plane and then spring together and retain a whisp of hair locked in the loop of the pin, between the overlap of its legs and the head bend.

Both forms of my novel hair-pins are especially advantageous in securing short ends of hair. They can obviously be made very cheaply in quantity, as well as in different sizes, depending upon the particular uses to which they are to be put. While I prefer to construct the pins from wire, they can of course be made from non-metallic strip or strand material which is sufficiently springy to predetermine functioning of the pins as hereinbefore described.

Having thus described my invention, I claim:

1. A hairpin consisting of a length of springy material medially bent to provide a rounded head and substantially coplanar prongs extending in parallel relation from the rounded head to opposed correspondingly-curved overlapping bights, said bights being separate and free so as in use, under induced axial twist, to admit between them a whisp of hair initially engaged below their overlap, and coacting to form a tor-

sionally strained substantially circular anchorage eye remote from the rounded head at a point midway of the longitudinal axis of the pin.

2. A hairpin consisting of a length of springy material medially bent to provide a rounded head and substantially coplanar prongs, such prongs embodying portions extending in parallel relation from the rounded head to outwardly curved corresponding bights thereby forming an elongate space with an enlarged substantially circular anchorage eye remote from said head, said bights having their free continuations reversely directed to overlap another immediately below the anchorage eye and under induced axial twist, admitting between them a whisp of hair initially engaged below their overlap and jointly coacting to form a gripping closure at a point midway of the longitudinal axis of the pin.

3. A hairpin consisting of a length of springy material medially bent to provide a rounded head and substantially coplanar prongs extending in parallel relation from the rounded head to opposed inwardly curved corresponding bights thereby forming an elongate eye in the plane of the pin, said bights occupying substantially parallel planes and having their center portions in spaced overlapping registration to jointly form a second smaller substantially circular anchorage eye in a plane at right angles to that of the pin, the free continuations of said bights being extended in parallel relation, and said smaller anchorage eye constituting, under induced axial twist incident to forced admission thereto of a whisp of the user's hair initially engaged below

35

their overlap, a gripping closure at a predetermined point in the longitudinal axis of the pin.

4. A hairpin consisting of a length of springy material medially bent to provide a rounded head and substantially coplanar prongs extending in parallel relation from the rounded head to opposed inwardly curved corresponding bights, thereby forming an elongate eye in the plane of the pin; said bights occupying substantially parallel planes, angularly directed relative to the common plane of the prongs, and having their center portions in spaced overlapping registration to jointly form a second substantially circular smaller anchorage eye in a plane at right angles to that of the pin, the free continuations of said bights being in parallel relation; and said smaller anchorage eye constituting, under induced axial twist incident to forced entry thereto of a whisp of the wearer's hair initially engaged below their overlap, a gripping closure remote from the rounded head at a point in the longitudinal axis of the pin below the elongate eye aforesaid.

5. A hairpin of springy material with its legs bent below the head bend into bights and overlapping side by side, so as to form a loop between their overlap and the head bend, and free to be forced apart, substantially perpendicular to the common plane of the legs, by a whisp of hair initially included between the legs below their overlap, so as to admit said whisp of hair into the loop and then spring together in opposed relation to retain the whisp firmly locked in said loop.
